CLAIM

The ornamental design for a transcranial stimulation device as shown and described.

DESCRIPTION

FIG. 1 is a top, front, left perspective view of a transcranial stimulation device;

FIG. 2 is a front view of the transcranial stimulation device;

FIG. 3 is a back view of the transcranial stimulation device;

FIG. 4 is a first side view of the transcranial stimulation device;

FIG. 5 is a second side view of the transcranial stimulation device;

FIG. 6 is a first top plan view of the transcranial stimulation device; and,

FIG. 7 is a second top plan view of the transcranial stimulation device.

The broken lines shown in the drawings are included for the purpose of illustrating portions of a transcranial stimulation device and forms no part of the claimed design.

1 Claim, 7 Drawing Sheets
